UNITED STATES PATENT OFFICE

HENRY P. PINKHAM, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH AND TERMINAL THEREFOR

Application filed March 26, 1930. Serial No. 438,998.

This invention relates to electric switches having stationary switch members including rigid conducting studs which are supported by insulating bushings and which carry at their lower ends the stationary contact members of the switch. The studs, or the contact members, must be adjustable vertically so that the contact faces of all of the contact members of the switch are in the same horizontal plane, or are so located that all of them will be engaged at the same time by the movable switch member. In the usual construction, the stud is provided with a long screw threaded portion at its lower end on which a screw threaded block is received which either constitutes, in itself, the stationary contact member or has the contact member secured thereto; and the screw threads have a nut which clamps the stud in adjusted axial position in the bushing. This construction is expensive in manufacture and also interposes a resistance joint in the conducting path between the stud and the contact member, which the present invention obviates.

It is therefore an object of this invention to provide an improved construction for a stationary switch member of an electric switch which will be cheaper to manufacture than those hitherto in use and which will have enhanced conductivity between the stud and the contact member carried thereby.

More specifically, it is an object of the invention to provide a stationary switch member wherein the stud is provided with an integral upset portion at the lower end thereof which constitutes the stationary contact block.

Insulating bushings as they are commercially produced vary slightly in their dimensions, especially those of porcelain or other molded materials, and it constitutes a further object of this invention to provide improved, convenient and economical means for the longitudinal adjustment of the stud relative to its supporting bushing thus to permit horizontal alignment of the stationary contact members for simultaneous engagement with the cooperating movable switch member.

A still further object of the invention is the provision of means permitting removal and replacement of the stationary contact members without disturbing the vertical or angular adjustment of the stud.

A further object is generally to improve the construction and operation of electric switches.

Fig. 1 is a side elevation of an electric switch embodying the invention, the enclosing casing being shown in section.

Fig. 2 is a sectional elevation showing in detail a stationary switch member of Fig. 1.

Fig. 3 is a section on line 3—3 of Fig. 2.

Fig. 4 is an end view of a brush unit.

Fig. 5 is a partial sectional detail of a modified construction.

As herein shown, the switch embodying the invention includes an enclosing casing which includes the open top receptacle 6 which is adapted to contain a body of insulating fluid to the level α , and a removable cover 8 which forms a closure for the open top of said receptacle and also constitutes a supporting frame for the stationary and movable switch members of the switch.

The stationary switch members 10, of which two are shown, are similar and each comprises a tubular insulating bushing 14 and an axial conducting stud 16 which extends therethrough and which carries at its lower end a stationary contact member 18. Said stationary switch members are received in apertures 20 in said cover 8 and are provided with attaching flanges 22 by which they are secured removably to said cover.

The movable switch member for the switch includes a horizontal bridging member 24 which is adapted to cooperate with and electrically connect the stationary contact members 18 in the usual manner and which is carried by a reciprocable switch or lifting rod 26 that is composed mainly of insulating material and is connected at its upper end with suitable switch operating mechanism, not necessarily shown.

In accordance with the present invention, the central conducting stud 16 of the stationary switch member is formed at its lowermost end with the relatively massive integral

terminal portion 30 which is formed by upsetting the end of the stud. Said terminal portion 30, as here shown, is of substantially rectangular section and provides an upper horizontal shoulder 32 and a lower flat contact attaching face 34 of substantial area. In some instances said terminal portion 30 may constitute, in itself, the main stationary contact member of the switch. The switch herein shown is of the inverted brush type and the main stationary contact member thereof includes a brush member comprising a plurality of superposed laminations having horizontal shank portions 36 and angularly related, downwardly directed toe portions 38 which terminate in a relatively horizontal contact face 40. As shown most clearly in Fig. 4, the shank portions 36 of said laminations are surrounded by a metallic sheath 42 which is substantially co-extensive with said shank portions and which serves to connect mechanically the several laminations of the brush whereby to provide a unitary brush structure. The sheath 42 and the shank portions of said laminations are usually mechanically and electrically connected together by solder. Said sheath 42 is provided with an upper plane surface 44 which is adapted to be clamped firmly against the lower face 34 of the terminal portion 30 whereby to provide a relatively extensive area of contact between the contact member and the stud. To this end, vertical passages are provided through the shank portion of said contact member and clamping bolts 48 are extended therethrough and are screw threaded into the threaded passages 46 in the terminal portion 30 of the stud. As shown most clearly in Fig. 3, the clamping bolts 48, of which two are here shown, are disposed in staggered relation on opposite sides of the longitudinal center line through the brush thus to distribute the pressure equally over the contacting surfaces 34 and 44 of said stud and contact member.

Said stud is also provided with an auxiliary contact or arcing member in the form of a cylinder 50 which is disposed transversely of the brush and substantially beneath the longitudinal axis of the stud. Said stationary arcing contact member 50 is supported between the depending arms 52 of a U-shaped bracket 54 by means of bolts 56 which are passed through said arms 52 and are screw threaded into the ends of said contact member. The middle connecting portion 58 of said bracket is secured beneath the heads of the attaching bolts 48 for the main brush member and consequently in electrical contact with the brush.

The bridging member 24 of the movable switch member comprises an inverted channel member having the depending side walls 60 and the flat upper back portion 62, the ends of which constitute horizontal contact

faces which cooperate with the contact faces 40 of the main stationary contact members. The movable arcing contact members comprising rollers 64 are supported on bolts 65 between parallel spaced arms 66 which are pivotally supported between the depending sides 60 of the movable brush member and are spring-urged in the usual manner into engagement with the cooperating fixed arcing members 50.

In accordance with the present invention, means are provided for adjusting the axial conducting stud 16 longitudinally in its supporting bushing 14 whereby to adjust the stationary contact member vertically.

The adjusting means includes a bushing 68 which is located loosely on the stud 16 above the head 30. Said bushing is provided with an externally screw-threaded lower end 70, and a hexagonal outstanding flange 72 at its upper end. An annular rib or lip 74 extends above the flange 72 and is located within the insulating spacing tube 76 of the bushing. The upper end of said tube is seated on a washer 78 which is located in an annular groove or recess 80 formed in the lower end of the bushing 14. The lower end of the tube is seated on a washer 84, which, in turn is seated on the upper face of the flange 72. Thus, the clamping pressure is transmitted through said bushing and tube to the insulator 14. The rib 74 holds the tube against axial displacement. An axially-long nut 86 is screw-threaded on the lower end of the bushing 68 and bears against the upper face of the head 30 of the stud. Thus, by holding the bushing 68 stationary and rotating the nut 86, in one direction or another, the stud can be raised and lowered in its insulating bushing 14 to adjust the height of the contact members carried by the stud. When the proper position for the contact members is determined, they are locked in position by means including a nut 88 which is screw-threaded on the screw-threaded upper end 90 of the stud and bears against the upper end of the insulator 14.

In the modification illustrated in Fig. 5, the outstanding flange 68a of the bushing 72 is at the bottom of the bushing and bears directly against the upper face of the integral head 30 of the stud. The upper portion of the bushing is located within the insulating tube 76 to hold it against lateral displacement and a nut 86 is threaded on the upper end of the bushing and bears against the lower end of the insulating tube.

The stud 16 is of uniform diameter above the enlarged head 30 or, at least, is not larger at the top than at the bottom, so that the bushing 68 can be placed in position thereon.

The above described arrangement has proven to be cheaper than the usual construction and to facilitate the labor of adjusting the position of the stationary contact

members. The switch is improved electrically since the head 30 is integral with the stud and thus the usual joint at this place, with its electrical resistance and consequent heating and reduction of current-carrying capacity of the switch is eliminated.

I claim:

1. A terminal for electric switches comprising the combination of an insulating bushing, a conducting stud therein which has an upset integral enlarged head at the lower end, a contact member carried by said head, a screw-threaded sleeve loose on said stud between said head and the lower end of said bushing, and a member threaded adjustably on said sleeve, said sleeve and member bearing separately on said head and the lower end of said bushing and constituting means which determines the position of said contact member with respect to said bushing.
- 10 2. A terminal for an electric switch comprising the combination of an insulating bushing having an abutment, a conducting stud therein which has a shoulder, a contact member carried by said stud, and an element of variable length disposed between said abutment and shoulder and having connected components which are adjustable lengthwise of the stud and which bear respectively upon said abutment and shoulder and constitute means to determine the position of said contact member with respect to said bushing.
- 15 3. A terminal for an electric switch comprising the combination of an insulating bushing having an abutment, a conducting stud therein which has a shoulder, a contact member carried by said stud, and a variable-length member disposed between said abutment and shoulder and having two elements which are adjustably screw threaded together and which bear respectively upon said abutment and shoulder and constitute means to determine the position of said contact member with respect to said bushing.
- 20 4. A terminal for electric switches comprising the combination of an insulating bushing, a conducting stud which extends entirely through said bushing and has a shoulder at its lower end, a contact member carried by the lower end of said stud, means for setting the position of said contact member with respect to said bushing including a variable length member having two elements which are adjustably connected together by said threads and which bear respectively upon said shoulder and upon the lower end of said bushing, and a clamping member which is screw threaded upon the upper end of said stud and bears against the upper end of said bushing.
- 25 5. A terminal for electric switches comprising the combination of an insulating bushing, a conducting stud therein having a shoulder which confronts the lower end of the bushing, a contact member carried by the bushing, and means which defines the position of said contact member with respect to said bushing including a variable-length member interposed between said head and the lower end of said tube and having means which engages

stud, and means for setting the position of said contact member with respect to the bushing including a screw threaded bushing which surrounds said stud between said shoulder and insulating bushing and has a nut screw threaded thereon, said screw threaded bushing and said nut bearing separately on said shoulder and the end of said insulating bushing.

6. A terminal for electric switches comprising the combination of an insulating bushing, a conducting stud therein having a shoulder which confronts the lower end of the bushing, a contact member carried by the stud, means for setting the position of said contact member with respect to the bushing including a screw threaded bushing which surrounds said stud between said shoulder and insulating bushing and has a nut screw threaded thereon, said screw threaded bushing and said nut bearing separately on said shoulder and the end of said insulating bushing, and a member having a screw-threaded connection with the upper end of said stud and bearing on the upper end of said insulating bushing.

7. A terminal for electric switches comprising the combination of an insulating bushing, a conducting stud therein having a shoulder, a contact member carried by said stud below said shoulder, means which determines the position of said contact member with respect to said bushing including a member which is interposed between said shoulder and the end of said bushing and bears against both and has means by which it is variable as to its axial length, whereby to define the spacing between said shoulder and bushing, and means carried by the upper end of said stud which applies axial pressure on the upper end of said bushing.

8. A terminal for electric switches comprising the combination of an insulating bushing, a conducting stud therein having an enlarged head at its lower end, a contact member carried by said head, a sleeve loose on said stud between said head and the lower end of said bushing and having an outstanding shoulder which bears upon the lower end of said bushing, and a nut screw threaded on said sleeve and movable axially thereon which bears against said head.

9. A terminal for electric switches comprising the combination of an insulating bushing, a conducting stud therein having an enlarged head located below the lower end of the bushing, a contact member carried by said head, an insulating tube which surrounds said stud above said head and has its upper end bearing upon the lower end of said bushing, and means which defines the position of said contact member with respect to said bushing including a variable-length member interposed between said head and the lower end of said tube and having means which engages

- said tube and restrains it against axial displacement, said member having two adjustably-connected and axially extensible members which bear separately on said head and the lower end of said tube.
10. A terminal for electric switches comprising the combination of an insulating bushing, a conducting stud therein having an enlarged head at the lower end thereof, a contact member carried by said head, an insulating tube surrounding said stud above said head and under said bushing, and having its upper end seated on the lower end of said bushing, and means to define the position of said contact member with respect to said bushing including a sleeve which is loose on said stud and which extends into said tube and constitutes means to hold it against lateral displacement, said sleeve having an outstanding flange which is seated upon the bottom of said tube and having a screw threaded portion beneath said flange, and a nut screw threaded on said sleeve and bearing upon said head.
11. A stationary switch member for an electric switch including a tubular insulating bushing, an axial conducting stud extended through said bushing having an integral enlarged end portion, an exteriorly screw threaded sleeve disposed on said conductor adjacent said enlarged end portion, an abutment member screw threaded on said sleeve, said sleeve and abutment member bearing separately on said enlarged end portion and on the end of said bushing, and a clamping nut screw threaded on the upper end of said stud and arranged to bear against the upper end of said insulating bushing.
12. An electric switch terminal comprising the combination of a tubular insulating bushing having an axial passage therethrough, a rigid conducting stud received within and extended through said passage at both ends thereof and having its lower end upset whereby to provide an enlarged contact attaching portion which is integral therewith, a contact member for the switch carried by the upset end portion of said stud and attaching bolts passed through said contact member and screw threaded into said stud for clamping said contact member detachably to said stud.
13. An electric switch terminal comprising the combination of a tubular insulating bushing having an axial passage therethrough, a rigid conducting stud received within and extended through said passage at both ends thereof and having its lower end upset whereby to provide an enlarged contact attaching portion which is integral therewith, a contact member for the switch carried by the upset end portion of said stud, attaching bolts passed through said contact member and screw threaded into said stud for clamping said contact member detachably to said stud.
14. An electric switch terminal comprising the combination of a tubular insulating bushing having an axial passage therethrough, a rigid conductor received within and extended through said passage at both ends thereof and having its lower end upset whereby to provide an end portion of increased cross sectional area, a contact member having a flat upper face located in contact with the enlarged lower end of said stud, clamping bolts passed through said contact member and screw threaded into said stud, an abutment member for the lower end of said bushing surrounding said stud adjacent the upset end portion thereof and capable of axial adjustment thereon, and clamping means at the upper extended end of said stud arranged to engage the upper end of said bushing whereby to urge said abutment member into engagement with the lower end of said bushing.
- In testimony whereof, I have signed my name to this specification.
- HENRY P. PINKHAM.
